H. C. ZIMMERMAN

CRADLE LOCK FOR GUN CARRIAGES

Filed Aug. 25, 1924

Inventor
Harry C. Zimmerman

W. N. Roach

Attorney

UNITED STATES PATENT OFFICE.

HARRY C. ZIMMERMAN, OF WASHINGTON, DISTRICT OF COLUMBIA.

CRADLE LOCK FOR GUN CARRIAGES.

Application filed August 25, 1924. Serial No. 734,060.

(GRANTED UNDER THE ACT OF MARCH 3, 1883; 22 STAT. L. 625.)

The invention described herein may be used by the Government, or any of its officers or employees in prosecution of work for the Government, or by any other person in the United States, without payment to me of any royalty thereon, in accordance with the act of March 3, 1883.

The subject of this invention is a cradle lock for gun carriages.

When mobile gun carriages are swung to their limbers for traveling the gun is retracted on its cradle to relieve the carriage of its unbalanced weight.

The principal object of the present invention is to provide means for locking the carriage in traveling position which also serves as an auxiliary support for the cradle and which will assist in taking up lost motion in the assembled parts about the pintle 20 to prevent excessive wear on the traversing and elevating mechanisms.

To these and other ends, my invention consists in the construction, arrangement, and combination of elements, described hereinafter and pointed out in the claims forming a part of this specification.

A practical embodiment of my invention is illustrated in the accompanying drawings, in which,

Fig. 1 is a view in side elevation of a gun carriage and cradle, showing the position of the cradle lock;

Fig. 2 is a front view of the cradle lock;

Fig. 3 is a detailed sectional view of the plunger; and

Fig. 4 is a detailed view of the bolt.

Referring to the drawings by numerals and characters of reference:

The gun carriage includes the usual axle A which supports the trails B, pintle C, and shield frame D. The pintle C supports the top carriage E, on which is trunnioned the cradle F, which mounts the usual reciprocal gun barrel G.

The cradle lock includes a tripodal support having a center leg 10 and outer legs 11-11, all of which are pivotally mounted on a common plane to the shield frame D.

The center leg 10 is a rod having an apertured base 12 receivable into a channel bracket 13 of the frame D and pivotally supported by means of a pin 14. The opposite extremity of the rod is formed with a trans-

verse tripod head 15 having upstanding ears 16 and inclined arms 17.

The outer legs 11-11 are tubular members suitably secured as by riveting to the arms 17 of the head. The opposite ends of the tubular members are secured to connecting rods 18 which are coupled to the bifurcated end 19 of a shaft 20 which is freely rotatable in a bearing 21 on the shield frame D. The tubular members may be formed for direct connection to the shaft 20, the rods 18 being provided to facilitate repair in the event of breakage.

The upstanding ears 16 on the tripod head are adapted to receive a lug 22 on the cradle F, the coupling being maintained by a bolt 23 passing through apertures in the ears and lug. The bolt 23 is held against disengagement by means of a spring actuated plunger 24 mounted on the head and adapted to enter a circular recess 25 in the bolt 23 when the bolt is fully home. The recess 25 is positioned at one end of a longitudinal slot 26 which terminates in a blind end 27 so that in withdrawing the bolt the plunger on being extracted from the recess 25 will ride in the slot 26 until brought up at the blind end 27 thus preventing the bolt from being completely withdrawn and possibly lost. Conversely, when the bolt is inserted the plunger will be guided by the slot 26 into the recess 25 so that the bolt will be automatically locked in place.

The tripodal support on being unlocked from the cradle may be swung downwardly where it will not interfere with the operation of the gun.

If desired, the free ends of the legs may be constructed to individually cooperate with the cradle lug, the coupling bolt passing through apertured terminals of the legs.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. A cradle lock for gun carriages including a tripodal support, the outer legs being tubular and universally mounted on the car-

- riage and the center leg pivotally mounted thereon, an apertured lug on the cradle, said center leg formed with a head having upstanding apertured ears adapted to receive the cradle lug therebetween and inclined arms for securing the outer legs to the head, a coupling bolt for connecting the cradle lug and head, said bolt formed with a longitudinal blind slot terminating at one end in a circular recess, and a plunger mounted in the head and engageable in the slot to hold the bolt in locked position and to normally prevent complete withdrawal of the bolt when in unlocked position.
- 15 2. A cradle lock for gun carriages including a tripodal support pivotally mounted on the carriage, a head formed on one of the legs of the support, the remaining legs being secured to the head, an apertured lug on the cradle, a bolt for coupling the head and cradle lug, said bolt formed with a longitudinal blind slot terminating at one end in a circular recess, and a plunger mounted in the head and engageable in the slot for holding the bolt in either locked or unlocked position.
- 20 3. A cradle lock for gun carriages including a tripodal support, the center leg pivotally mounted on the carriage and formed

with a head having inclined arms, the outer legs being tubular and secured to said arms, a connecting rod secured to each of said outer legs, a rotatable shaft mounted on the carriage and pivotally supporting the connecting rods, a lug on the cradle, and means 30 for coupling the head to the cradle lug.

4. A cradle lock for gun carriages including a tripodal swinging support, means for mounting said support to the carriage, a tripod head formed with upstanding apertured ears, an apertured lug on the cradle, a coupling bolt insertable through the ears and lug, said bolt formed with a longitudinal blind slot terminating at one end in a circular recess, and a plunger mounted in 40 the head and engageable in the slot for holding the bolt in either locked or unlocked position.

5. A cradle lock for gun carriages including a tripodal swinging support, means for mounting said support to the carriage, a tripod head formed with upstanding apertured ears, an apertured lug on said cradle, a coupling bolt insertable through the ears and lug, and means mounted in the head and co-operating with the bolt for holding the bolt 50 in either locked or unlocked position.

HARRY C. ZIMMERMAN.
